CLAIM

The ornamental design for a heel element for ski binding, as shown and described.

DESCRIPTION

FIG. 1 is a perspective view of a heel element for ski binding, showing our new design;

FIG. 2 is a top plan view thereof;

FIG. 3 is a left side elevational view thereof, the right side elevational view being a mirror of the left side elevational view and therefore not shown;

FIG. 4 is a bottom plan view thereof;

FIG. 5 is a front elevational view thereof; and,

FIG. 6 is a rear elevational view thereof.

FIG. 1

FIG. 2

FIG. 3

FIG. 4

FIG. 5

FIG. 6
